UNITED STATES PATENT OFFICE

148,205

DESIGN FOR A FOOT-PROPELLED VEHICLE

Omer L. Woodson, Los Angeles, Calif.

Application August 16, 1946, Serial No. 132,585

Term of patent 14 years

(Cl. D34—15)

To all whom it may concern:

Be it known that I, Omer L. Woodson, a citizen of the United States of America, residing in the city of Los Angeles, in the county of Los Angeles, State of California, have invented a new, original, and ornamental Design for a Foot-Propelled Vehicle, of which the following is a specification, reference being had to the accompanying drawing, forming a part thereof.

Fig. 1 is a perspective view of the vehicle as seen from the right side; and

Fig. 2 is a plan view of the device illustrated in Fig. 1.

The appearance of the right side is a mirror image of that of the left.

I claim:

The ornamental design for a foot-propelled vehicle, substantially as shown and described.

OMER L. WOODSON.
